US00D603356S

(12) United States Design Patent
Sterzick et al.

(10) Patent No.: US D603,356 S
(45) Date of Patent: * Nov. 3, 2009

(54) PORTABLE TELEPHONE

(75) Inventors: Mark Sterzick, Rancho Dominguez, CA (US); Jeff Jones, Rancho Dominguez, CA (US); Dimitre (Miki) Mehandjiysky, Rancho Dominguez, CA (US); Alex Chon, Rancho Dominguez, CA (US); Steven Tkachuk, Rancho Dominguez, CA (US); Naoki Shimada, Rancho Dominguez, CA (US)

(73) Assignee: Samsung Electronics Co., Ltd., Suwon, Kyunggi-Do (KR)

() Term: 14 Years

(21) Appl. No.: 29/312,893

(22) Filed: Nov. 19, 2008

(51) LOC (9) Cl. 14-03

(52) U.S. Cl. .... D14/138 G

(58) Field of Classification Search ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3

See application file for complete search history.

(57) CLAIM

The ornamental design for a portable telephone, as shown and described.

DESCRIPTION

FIG. 1 is a top front perspective view of a portable telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
